Primary Examiner — Paula Greene

(74) Attorney, Agent, or Firm — Brinks Gilson & Lione

(57) **CLAIM**

The ornamental design of the installation panel for vehicle, as shown and described.

DESCRIPTION

FIG. 1 is a perspective view of an installation panel for vehicle showing the new design;
 FIG. 2 is a front view thereof;
 FIG. 3 is a rear view thereof;
 FIG. 4 is a left-side view thereof;
 FIG. 5 is a right-side view thereof;
 FIG. 6 is a top view thereof; and,
 FIG. 7 is a bottom view thereof.

The broken lines are for environmental purposes only and do not form any part of the claimed design.
